W. P. MURPHY.
CAR ROOF.
APPLICATION FILED DEC. 7, 1918.

1,295,192.

Patented Feb. 25, 1919.

UNITED STATES PATENT OFFICE.

WALTER P. MURPHY, OF NEW YORK, N. Y., ASSIGNOR TO P. H. MURPHY COMPANY, OF PARNASSUS, PENNSYLVANIA, A CORPORATION OF PENNSYLVANIA.

CAR-ROOF.

1,295,192.

Specification of Letters Patent. Patented Feb. 25, 1919.

Application filed December 7, 1918. Serial No. 265,707.

To all whom it may concern:

Be it known that I, WALTER P. MURPHY, a citizen of the United States, and a resident of the city of New York, in the county of New York and State of New York, have invented a new and useful Improvement in Car-Roofs, of which the following is a specification.

This invention relates to outside metal car roofs of the type shown and described in the C. C. Murphy Patent No. 1,133,493, dated March 30, 1915, wherein the roof sheets are pivotally mounted on the substructure on opposite sides of the ridge, and it relates particularly to the intermediate running board saddle or anchor saddle used in this type of roof. In the above roof, difficulty is sometimes experienced with the wooden anchor saddles, whose purpose is to hold the roof sheets in engagement with the pivots, and also hold the roof sheets in position on the substructure. These wooden saddles are provided with holes through which the bolts for securing the saddles to the substructure pass. In actual practice the saddle is liable to rot out and wear around the bolt hole; and the saddle is also liable to shrink and warp and the portion of the saddle which rests on the sheet is liable to split off. In such event, the sheet is liable to ride up on its pivot and thus become dislocated. This also allows cinders and grit to accumulate, and the rubbing action is liable to wear the galvanizing off the sheets and thus cause the sheets to rust; while the cinders which contain sulfur will effect rapid corrosion. This action is aggravated by the moisture retained in the wood, which causes the wood to swell and clamp the sheets too tightly; whereas the engagement of the saddle with the sheet is liable to be insufficient when the wood is thoroughly dry.

The principal object of the present invention is to produce a sheet anchor which will overcome the disadvantages hereinbefore mentioned. Another object is to securely fasten the sheet anchor to the car so that it will not become loose during the service of the car. Other objects are: to prevent leaks around the securing bolt; to cheapen the cost of manufacture and application of the anchor saddle; to reduce the size thereof; and to improve the appearance of the roof. The invention consists in the improved metal sheet anchor for holding the

sheets on their pivots, and in the combinations and arrangements of parts herein-after described and claimed.

In the accompanying drawing, which forms part of this specification, and wherein like symbols refer to like parts wherever they occur,

Figure 1 is a plan view of a car roof embodying my invention, parts of the roof being shown broken away to more clearly illustrate the invention;

Fig. 2 is an enlarged plan view of the ridge portion of the roof in the region of the sheet anchor;

Fig. 3 is a cross section through the ridge portion of the roof on the line 3—3 in Fig. 2;

Fig. 4 is a cross section through the eaves portion of the car on the line 4—4 in Fig. 1; and

Fig. 5 is a cross section through one of the transverse seams on the line 5—5 in Fig. 1.

The roof is illustrated in the accompanying drawing and comprises side sheathing 6, roof sheathing 7, supported at the eaves by side plates 8, and at the ridge by means of a ridge pole 9, all of well known construction. The roof sheets 10 are arranged transversely of the car in pairs on opposite sides of the ridge and are provided at their side and ridge margins with inwardly hooked upstanding flanges 11 and 12. At their eaves ends, the sheets are doubled under, as at 13, parallel with the body portion of the roof sheets but spaced far enough below said body portion to accommodate the rebent portion 14 of a continuous eaves flashing strip 15. This flashing strip lies in a rabbet formed in the eaves portion of the roof sheathing and is turned down over the side of the car and secured to the side sheathing by nails or other suitable securing means. At the side margins, each pair of roof sheets is spaced from the adjacent pairs; and, in the space thus formed, are arranged mullions or battens 16. These mullions 16 extend transversely from eaves to ridge on opposite sides of the roof and are of less width than the spaces between the side margins of the roof sheets. Transverse seam caps 17, of inverted channel shaped section, straddle the mullions 16 and the adjacent side margins of the roof sheets, and the lower edges of the side walls of said seam caps have inwardly and upwardly inclined flanges 18 which interlock with the

roof sheet flanges 11 at the side margins of the roof sheets. The transverse seam caps extend from eaves to ridge, and their eaves ends are held down by bending their 5 ends under the ends of the mullions or in any other desired manner.

The sheets are spaced apart at the ridge, and a ridge seam cap 19 similar in cross section to the transverse seam caps 17 straddles the adjacent ridge margins of each 10 pair of sheets. The lower edges of the side walls of the ridge seam cap have flanges 20 which interlock with the hooked flanges 12 at the ridge margins of the roof sheets in a 15 manner similar to the transverse seam construction. The ridge ends of the transverse seam caps and the adjacent ends of the ridge seam caps are covered by the usual four-way corner caps 21. The corner caps are 20 secured to the substructure in a usual manner by bolts which also secure the running board saddle 22 in position. Running boards 23 are secured to the running board saddles which rest on the transverse seam 25 caps and are supported by the mullions, thus permitting movement of the roof sheets under the seam covers.

Each sheet of a pair of oppositely disposed roof sheets is pivoted to the roof sub- 30 structure at the middle portion of its ridge end by a sheet metal saddle plate 24. The saddle plates straddle the ridge portion of the car and are provided near their end portions with inverted cup shaped pivot bosses 35 having inclined side walls which fit into similar or counter-part upstanding bosses 26 which are centrally located in the sheets near their ridge ends. The oppositely disposed bosses 26 of each pair of roof sheets 40 are held in position on the pivot bosses 25 of the saddle plate 24 by means of a sheet anchor saddle 27 located at the ridge on a transverse line between the oppositely disposed bosses 26 of each pair of roof sheets. 45 This anchor saddle, which is preferably made in the form of a malleable casting comprises an inverted channel shaped portion 28 having lateral portions 29 extending outwardly from the lower edge of each side 50 wall of the channel shaped portion 28. The channel shaped portion of the anchor saddle straddles the ridge seam cap and the anchor saddle is secured to the substructure by means of a vertical bolt 30, which passes 55 through a bossed up hole 31 in the ridge seam cover.

The ends of the laterally extending portion 29 of the anchor saddle are provided with flanges 32 which are curved or forked 60 to fit the circular bosses of the roof sheets 26 and are also inclined upwardly and outwardly to correspond to the inclination of the side walls of the bosses. The vertical bolt 30, which secures the anchor saddle to 65 the substructure, extends upward through

the ridge pole 9 and roof sheathing 7, and passes through a hole in the saddle plates 24, thus holding this member in position. The bolt then passes through the bossed up hole 31 in the ridge seam cover and is 70 threaded into a hole in a boss 33 which projects upwardly from the channel shaped portion 28 of the anchor saddle. The bolt is prevented from working loose from the anchor saddle by means of a lock nut 34 75 which is screwed down tight on the boss 33 of the anchor member and also prevents water following the bolt and reaching the interior of the car. The top of the anchor saddle is provided with a stiffening rib 35 80 which extends from the medial boss 33 to the inclined circular flanges 32 at the ends of the anchor saddle. The threaded hole in the boss 33 of the anchor saddle, into which the upper end of the bolt 30 is threaded, is 85 counter-sunk on its under side to receive the bossed up portion 31 of the ridge seam cover. This prevents water, which may get between the underside of the bottom of the channel shaped portion 28 of the anchor and 90 the top of the ridge seam cap, from entering the car.

By the arrangement described, a water tight joint between the anchor saddle and the seam caps is obtained, and the tendency 95 of the anchor saddle bolts to become loose is overcome.

What I claim is:

1. A car roof having an upwardly extending pivot member, a roof sheet having an 100 upwardly extending hollow boss fitting over said pivot, and an anchor member located upon said roof sheet, said anchor member being secured to the car and having a concave end portion engaging the hollow boss 105 of said roof sheet for holding said boss on said pivot member.

2. A car roof having upwardly extending pivot members on each side of the ridge, roof sheets arranged on each side of the ridge 110 and having upwardly extending bosses formed thereon fitting over adjacent pivot members, and anchor members located above said roof sheets, said anchor members being secured to the car and having incurved end 115 portions adapted to engage the adjacent up-standing bosses of the roof sheets for holding said bosses on the respective pivot members.

3. A car roof having upwardly extending 120 pivot members oppositely disposed on each side of the ridge, roof sheets arranged on each side of the ridge and having upwardly extending hollow bosses fitting over the adjacent pivot members, and an anchor member 125 located above said roof sheets, said anchor member being secured to the ridge of the car and extending on opposite sides of the ridge, the opposite end portions of said anchor member being concaved to fit 130

the upstanding bosses of the roof sheets for holding said bosses on their respective pivot members.

4. A car roof having upwardly extending pivot members oppositely disposed on each side of the roof, oppositely disposed roof sheets extending transversely of the car on each side of the roof, said roof sheets having upwardly extending bosses formed there-
10 in fitting the adjacent pivot members, and an anchor member secured to the ridge and extending on opposite sides thereof above the roof sheets, said anchor being disposed transversely of the car and having concave
15 end portions adapted to fit the bosses of said sheets, and means for securing said anchor member to the roof, said means comprising a bolt extending upward from the roof substructure and adapted to be threaded
20 into the anchor member.

5. A car roof having upwardly extending pivot members oppositely disposed on each side of the car, roof sheets arranged transversely of the car in pairs, each roof
25 sheet of a pair having an upwardly extending boss formed in its center near its ridge end fitting the adjacent pivot members, an anchor member located above each pair of sheets and extending transversely on a line
30 between the bosses of each pair of roof sheets, said anchor member having incurved end portions adapted to fit the bosses of each pair of roof sheets, and a bolt extending upwardly from the roof substructure, said
35 bolt being threaded into the anchor member and having a nut on its upper end adapted to lock the anchor member to said bolt.

6. An outside metal car roof having oppositely disposed pivot members projecting
40 upwardly from the substructure on each side of the ridge, roof sheets arranged transversely of the car in pairs, the sheets of each pair being arranged on opposite sides of the ridge and having upwardly ex-
45 tending bosses formed in their middle near the ridge fitting over the oppositely disposed pivot members, ridge seam covers loosely connecting the ridge margins of said sheets, and an anchor member located above
50 each pair of sheets and adapted to straddle the ridge cover, said anchor member being arranged crosswise of the car and in a trans-
verse line between the boss of each pair of sheets, said anchor member being secured

to the car at the ridge and having concave ends adapted to engage the adjacent sides of the bosses of each sheet of a pair.

7. An outside metal car roof having oppositely disposed pivot members projecting upwardly from the substructure on each side of the ridge, roof sheets arranged transversely of the car in pairs, the sheets of each pair being arranged on opposite sides of the ridge and having upwardly extending bosses formed in their middle near the ridge fitting over the oppositely disposed pivot members, ridge seam covers straddling the ridge margins of each pair of roof sheets, a transversely arranged anchor member adapted to straddle the ridge cover between the bosses of each pair of sheets, said ridge covers having bossed-up portions located in a transverse line between the bosses of each pair of roof sheets and adapted to project into the underside of said anchor member, and a bolt for securing the anchor member to the car, said bolt extending upwardly from the car substructure through the bossed-up portion of the ridge caps and being threaded into the anchor member and having a nut on its upper end.

8. An anchor member for a car roof, said anchor member being adapted to be secured to the substructure at the ridge and having an arm terminating in a concave end adapted to engage the upwardly extending boss of a roof sheet.

9. An anchor member for a car roof, said anchor member being adapted to be secured to the substructure at the ridge and being channeled on its under side at its middle, said anchor member having arms extending in opposite directions from said channel, said arms terminating in concave ends adapted to fit upwardly extending bosses formed in the roof sheets.

10. An anchor member for a car roof, said anchor member having its middle portion adapted to be secured at the ridge of the car and having arms inclining downwardly from said middle portion to conform to the pitch of the roof, and terminating in concave ends adapted to engage upwardly extending bosses formed in the roof sheets.

Signed at Chicago this 2nd day of December, 1918.

WALTER P. MURPHY.
